UNITED STATES PATENT OFFICE.

EDWIN H. FORD, OF WABASH, INDIANA.

WATER-METER SUPPORT AND CONNECTION.

1,262,083.

Specification of Letters Patent.

Patented Apr. 9, 1918.

Application filed April 13, 1917. Serial No. 161,774.

To all whom it may concern:

Be it known that I, EDWIN H. FORD, a citizen of the United States, residing at Wabash, in the county of Wabash and State 5 of Indiana, have invented certain new and useful Improvements in Water-Meter Supports and Connections, of which the following is a specification.

The adoption and use by public water 10 service companies of devices for setting and connecting water meters to branches of service pipes, where the meters are placed some distance below the surface of the ground in meter-boxes, is largely determined by the 15 following considerations, first, whether the meters can easily and readily be placed and clamped into operative position; second, whether the mechanisms for clamping the meters in position can easily be reached and 20 manipulated from the surface of the ground; and, third, whether the meters can easily and readily be removed from operative position.

In many of the present devices upon the 25 market for setting and connecting water meters to the branches of service pipes the mechanisms for clamping the meters into operative position are situated so that the meters can be seated and removed only after 30 considerably annoyance and labor from within the narrow confines of conventional styles of meter-boxes.

The present invention relates to a device 35 for supporting and for clamping water meters within meter-boxes; and the object of a the invention consists in the provision of a device of the above character whereby meters can easily be placed and clamped into position; the clamping mechanism being 40 easily accessible from the surface of the ground, and which is simple in construction and efficient in operation.

I accomplish the above objects of the invention, and such others as may appear from 45 a perusal of the specification and claims, by means of the construction illustrated in the accompanying drawings forming a part hereof, in which—

Figure 1 is a top or plan view of the construction. Fig. 2 is a front elevation of the 50 construction shown in Fig. 1. Fig. 3 is a side elevation of the construction shown in Figs. 1 and 2. Fig. 4 is a fragmentary detail view partly in front elevation and partly 55 in section, on the line 4—4 in Fig. 3.

Referring to the drawings, 10 represents a meter-box, and 11 the vertical branches of the service pipe, the said branches extending into the meter-box in substantially parallel direction. The threaded free end 60 of each pipe branch 11 is screwed into a threaded opening arranged in the central portion of an arm 15 having a passageway 16 for conducting the water therethrough. See Fig. 4. Arms 15 are provided with suitable shoulders 19 which extend partly around the lower portion of the openings of passageways 16 to form saddles for supporting the spuds 18 of a meter 20. Arms 15, when arranged in operative position on 70 the ends of pipe branches 11, stand oblique to a vertical plane through the axes of pipe branches 11, so as to bring the ends of the arms out to or near vertical planes extending past the side edges of meter 20. This 75 is important for the reason that the ends of arms 15 carry the clamping bolts 25 and place the latter in position to render them readily accessible from above. One end of 80 each bolt 25 is provided with right hand threads where it engages the corresponding arm 15 and the opposite end of each bolt is provided with left hand threads where it engages the corresponding arm 15. Each bolt 25 is further provided with an integral 85 wheel 26 having a grooved periphery so as to render more easy the rotation of said bolts from the surface of the ground.

When meter 20 is placed into saddles 19 the joints between the metal parts are sealed 90 against leakage by means of the gaskets 30. In the operation of clamping meter 20 tightly between arms 15 the lower bolt 25 is initially rotated to bring arms 15 toward each other to a point merely to admit the 95 introduction of the particular type of meter and gasket to be installed and no more. The lower bolt, therefore, for all intent and purpose becomes a permanent part of the structure, as all subsequent manipulations of 100 clamping the meter and arms against the gaskets, and the loosening of the parts for the removal of the meter are entirely effected and controlled by the upper bolt 25.

The present invention is a simple and 105 efficient construction for mounting and connecting water meters to the branches of water service pipes within the narrow confines of a conventional style of meter-box, and the dotted position in Fig. 3 shows how 110

readily a meter can be lowered or raised from its operative position free from interference.

Having thus fully described my said invention, what I desire to secure by Letters Patent, is—

1. In combination, a pair of pipe branches, meter-supports comprising opposite arms arranged on the free ends of said pipe branches and having passageways for conducting water between the pipe branches and the meter, means for adjustably connecting and for initially spacing one pair of ends of the arms a determined distance apart, and means for adjustably connecting the opposite ends of the arms and for impinging the latter against the meter.

2. In combination, a pair of pipe branches, meter-supports arranged on the free ends of said pipe branches and disposed obliquely to the longitudinal axes of said branches, said supports having passageways for conducting water between the branches and the meter, means for connecting and for spacing the lower ends of the meter-supports a determined distance apart, and means for connecting the upper ends of the meter-supports and for impinging the latter against the meter.

3. In combination, a meter-box, a pair of pipe branches extending into said box, meter-supports comprising opposite arms arranged on the free ends of said pipe-branches and having passageways for conducting water between the latter and the meter, means for adjustably connecting and for initially spacing one pair of ends of the

arms a determined distance apart, and means for adjustably connecting the opposite ends of the arms and for impinging the latter 40 against the meter.

4. In combination, a meter-box, a pair of pipe branches extending into said box, meter-supports comprising opposite arms arranged on the free ends of said pipe-branches and having passageways for conducting water between the latter and the meter, means carried by said arms for holding the meter in operative position, means for adjustably connecting and for initially 50 spacing one pair of ends of the arms a determined distance apart, and means for adjustably connecting the opposite ends of the meter-supports and for impinging the latter 55 against the meter.

5. In combination, a meter-box, a pair of pipe branches extending into said box, meter-supports arranged on the free ends of said pipe-branches and disposed obliquely to the longitudinal axes of said branches, 60 said supports having passageways for conducting water between the latter and the meter, means for adjustably connecting and for initially spacing the lower ends of the supports a determined distance apart, and means for connecting the upper ends of the supports and for impinging the latter 65 against the meter.

In witness whereof I have hereunto set 70 my hand and seal at Wabash, Indiana, this 3rd day of April, A. D. one thousand nine hundred and seventeen.

EDWIN H. FORD. [L. S.]
